UNITED STATES PATENT OFFICE

WALTER R. SCHLAGE, OF SAN FRANCISCO, CALIFORNIA, ASSIGNOR TO SCHLAGE LOCK COMPANY, OF SAN FRANCISCO, CALIFORNIA, A CORPORATION OF CALIFORNIA

DOORKNOB

Application filed December 6, 1929. Serial No. 412,220.

This invention relates to door knobs and especially to improvements in the structure which permits ready change in the design or ornamental appearance of the knob.

5 Door knobs come under the general heading of lock hardware. Hardware of this character is subject to constant changes in design, each change in design, usually requiring entirely new knobs, escutcheon plates 10 etc. It would, accordingly, be exceedingly advantageous if the general design or appearance of hardware of this character could be readily changed without making or manufacturing entire new parts.

15 The structure shown in this application pertains especially to door knobs, the object being to provide a knob having an annular seat or depression in its outer surface for the reception of an ornamental plate whereby the 20 design or appearance of the knob may be changed; and further in providing means whereby the plate may be secured in the recess and against removal.

The invention is shown by way of illustration in the accompanying drawings, in 25 which:—

Fig. 1 is a front view showing the outer surface of the knob,

Fig. 2 is a central vertical longitudinal section of the knob and the spindle upon which it is supported, said view also showing one method of securing an ornamental plate with relation to the spindle,

Fig. 3 is a perspective view of an ornamental plate showing the inner surface thereof and the spring prongs whereby the plate is secured to the spindle,

Fig. 4 is a view, similar to Fig. 2, showing another form of plate securing means.

40 Referring to the drawings in detail, particularly Figs. 1, 2 and 3, A indicates a knob; 2 a hollow or tubular spindle; 3 an ornamental plate, which functions as a closure for the outer end of the spindle and also as an 45 ornamentation for the knob proper. The knob is provided with an annular recess or depression 4 in its outer face to receive and protect the ornamental plate, and it is also provided with a central passage 5 through 50 which the spindle extends, the knob being se-

cured on the spindle by a flange 6 on the outer end of the spindle engaging lugs 7 in the knob and by a friction nut 8 which engages a recess formed in the inner face of the knob. The outer end of the spindle is also provided 55 with an annular flange such as indicated at 9 and this forms one of the means of securing the ornamental plate.

In the present instance the inner face of the plate is provided with a pair of spring 60 legs or prongs such as shown at 10. When the plate 3 is forced into the recess 4 the legs 10 are passed within the flange 9 and by engaging the flange frictionally secures the plate against removal. This method permits 65 the plate to be removed if other ornamental plates or effects are desired. If a more or less permanent connection is desired the prongs may be bent, as shown at 11 in Fig. 4. By bending the prongs in this manner hook-shaped members are formed which engage 70 the flange 9, thereby positively securing the plate against removal when inserted.

A variety of ornamental plates, such as shown at 3 in Figs. 1 and 2, may be employed. 75 They may be constructed of metal, or otherwise, and may be ornamented in any suitable manner. Furthermore, it is obvious that the ornamental surface may be colored in such a manner as to match the trim, or woodwork, 80 of a room and an exceedingly pleasant and artistic effect may accordingly be obtained.

It should also be noted that the ornamental plate lies within the outer face 12 of the recess. This is important as the ornamental plate is protected against being struck or accidentally marred or injured by being depressed or placed below the surface 12.

While the ornamental plate has been shown 85 in connection with a glass knob, it is obvious that the knob may be constructed of porcelain, metal, or any other suitable material.

While certain features of the present invention are more or less specifically described, 95 I wish it understood that various changes may be resorted to within the scope of the appended claims. Similarly, that the materials and finishes of the several parts employed may be such as the manufacturer may 100

decide, or varying conditions or uses may demand.

Having thus described my invention, what I claim and desire to secure by Letters Patent is:

- 5 1. In a structure of the character described a knob having an annular recess formed in its outer face and a central opening communicating therewith and extending through the knob, a hollow spindle extending from the recess through the knob, means securing the knob on the spindle, a plate seated in the recess and forming a closure for the outer end of the hollow spindle, prongs secured on the plate, and means within the spindle with which the prongs are engageable to secure the plate against removal.
- 10 2. In a structure of the character described a knob having an annular recess formed in its outer face and a central opening communicating therewith and extending through the knob, a hollow spindle extending from the recess through the knob, means securing the knob on the spindle, a plate seated in the recess and forming a closure for the outer end of the hollow spindle, hook-shaped prongs secured to the plate, and means within the spindle with which the hook-shaped prongs are engageable to secure the plate against removal.
- 15 3. In a structure of the character described a knob having an annular recess formed in its outer face and a central opening communicating therewith and extending through the knob, a hollow spindle extending from the recess through the knob, means securing the knob on the spindle, a plate seated in the recess and forming a closure for the outer end of the hollow spindle, hook-shaped prongs secured to the plate, and means within the spindle with which the hook-shaped prongs are engageable to secure the plate against removal.
- 20 4. In a structure of the character described a knob having an annular recess formed in its outer face and a central opening communicating therewith and extending through the knob, a hollow spindle extending from the recess through the knob, means securing the knob on the spindle, a plate seated in the recess and forming a closure for the outer end of the hollow spindle, hook-shaped prongs secured to the plate, and means within the spindle with which the hook-shaped prongs are engageable to secure the plate against removal.
- 25 5. In a structure of the character described a knob having an annular recess formed in its outer face and a central opening communicating therewith and extending through the knob, a hollow spindle extending from the recess through the knob, means securing the knob on the spindle, a plate seated in the recess and forming a closure for the outer end of the hollow spindle, hook-shaped prongs secured to the plate, and means within the spindle with which the hook-shaped prongs are engageable to secure the plate against removal.
- 30 6. In a structure of the character described a knob having an annular recess formed in its outer face and a central opening communicating therewith and extending through the knob, a hollow spindle extending from the recess through the knob, means securing the knob on the spindle, a plate seated in the recess and forming a closure for the outer end of the hollow spindle, hook-shaped prongs secured to the plate, and means within the spindle with which the hook-shaped prongs are engageable to secure the plate against removal.
